Attorney

UNITED STATES PATENT OFFICE

THOMAS J. CHILDRESS, OF WAYNESBORO, VIRGINIA

COMBINED RULER SQUARE AND MITER SQUARE

Application filed November 23, 1927. Serial No. 235,239.

The present invention relates to carpenters' rules of the folding type and has for an object to provide a pair of arms pivotally mounted at one end for swinging movement at opposite sides of the rules whereby to combine therewith to form a square and a miter square at opposite sides of the rule.

A further object of the invention is to provide adjustable means for the arm mounted on the rule for securing the respective arms in various adjusted positions.

A still further object is to provide an article of this character of simple and practical construction, which may be incorporated in the construction of the rule without interfering with the normal use thereof, which is inexpensive to manufacture and otherwise well adapted for the purposes for which it is intended.

Other objects and advantages reside in the special construction and combination of the various elements comprising the invention, reference being had to the accompanying drawings forming a part hereof, wherein:

Figure 1 is a view in elevation of one side of the rule shown in folded position, the arm constituting the miter square being shown in cooperating position with respect thereto and a fragment of the opposite arm constituting the square being shown in dotted lines in its cooperating position at the opposite side of the rule.

Figure 2 is an edge elevational view and Figure 3 is an end view thereof.

Referring now to the drawing in detail, my invention contemplates the use of a carpenter's rule indicated at 5 of the folding type, having its outer edges 6, when in folded position provided with a longitudinally extending groove, the area of which is indicated by the dotted line 7 in Figure 1 of the drawing, the upper ends of each groove having a pivot pin 8 extending transversely therethrough providing a mounting for one end of a swinging arm 9.

The arm 9 disposed at the opposite edges of the rule are adapted normally to seat within the groove 7 in substantially enclosed relation therewithin. The notch 10 is formed at each edge of the rule exposing a portion

of the outer edge of the arm for finger gripping so as to enable the arm to be withdrawn from their seated position within the recess. A recess or aperture 11 may be formed in the arm adjacent the outer edge thereof within 55 which a pointed instrument or the finger nail of the user may be inserted to enable the arm to be firmly gripped when desired for moving the same outwardly with respect to the ruler.

Adjacent the pivoted end of each of the arms is an adjusting plate 12 having a tongue 13 formed at one side thereof fitted within a shallow groove 14 formed in the edge of the rule permitting the plate to slide longitudinally therein. A slotted opening 15 is formed in the plate through which an adjusting screw 16 may be introduced whereby to secure the plate in adjusted position with respect to the rule 5.

The end of each of the plates 12 are adapted to form an abutment for the outer edge of the adjacent arm 9, in a manner as clearly illustrated in Figure 1 of the drawing, the plate disposed at the side of the ruler adjacent the arm 17 shown in dotted lines forming the limitation for the outward movement thereof whereby to enable said arm to cooperate with the rule in forming a square, whereas the abutting end of the opposite plate adapted for engagement with the edge of the opposite arm 9 is beveled inwardly as shown at 18 so as to form an abutment at the outer edge of said arm when disposed in outwardly inclined position enabling the same to cooperate with the rule for constituting a miter square. It is apparent that the angle at which the arm 9 may be disposed with respect to the rule may be quickly adjusted by sliding the coating plate 12 upwardly or 90 downwardly corresponding with the extent to which the arm 9 is desired to be moved.

The outer edge of each of the arms 9 and 17 may be provided with a scale 19 to form a measurement for the work with respect to 95 which the arms are used. The scale also continues along the edges of the arm adjacent the plate 12 and the plates likewise are provided with similar scale markings 20 whereby to cooperate with the scale of the arm to 100

indicate a predetermined adjustment of the plate.

It is obvious that the invention is susceptible of various changes and modifications, without departing from the spirit or scope of the invention or sacrificing any of its advantages, and I accordingly claim all such forms of the device to which I am entitled.

Having thus described my invention, what I claim as new is:

- 10 1. In combination, a folding rule having longitudinally extending recesses formed in its opposite edges when in folded position, arms pivotally mounted at one end within said recesses with their opposite ends adapted for outward swinging movement with respect to the rule, and stop means adjustably carried by the rule and engageable by the arm for regulating the extent of outward movement of said arm, said stop means and the adjacent edges of the rule each having portions of the scale marked thereon and cooperating to indicate a predetermined adjustment of the stop means.
- 15 2. In combination, a folding rule having longitudinally extending recesses formed in its outer edges when in folded position, arms pivotally mounted at one end in said recesses and adapted for outward swinging movement with respect to the rule and a pair of adjustably mounted stop plates carried by the rule and engageable by the respective arms for controlling the extent of outward movement of said arms, said stop plates and the adjacent edges of the rule each having portions of a scale formed thereon and cooperating to indicate a predetermined adjustment of the stop plate.

In testimony whereof I affix my signature.

40 THOMAS J. CHILDRESS.
